HEAT ACCUMULATOR

Hans Pohl, Burgbrohl, and Eduard Pohl, Rhon-dorf, Germany; said Hans Pohl assignor to firm Stein- und Thonindustriegesellschaft "Brohl-thal", Burgbrohl, Germany

Application May 17, 1930, Serial No. 453,309
In Germany January 3, 1928

4 Claims. (Cl. 263—51)

The present invention relates to the construction of heat accumulators of which the checker work is divided into various superposed zones which follow one another in the arrangement of 5 the flow of the gases.

The state of the art of blast furnace mouth gas purification enables the blast furnace engineer, when erecting heat accumulators to reduce the width of the passages and the thickness of the 10 walls considerably further than was hitherto possible, as there is no longer any liability to the easy clogging up of small passage areas by the thoroughly cleaned gases which are available at the present time.

15 In accordance with the reduction in volume of the heating gases as a result of the continued drops in temperature the heat accumulators are provided with passages which become smaller towards the bottom. In the lower portions of the 20 heat accumulators it is of advantage, as regards a good economy in heat and provided that a thoroughly purified gas is available, to use passages of small cross sectional area and stones of small thickness.

25 If it was desired to form this lower portion of the heat accumulator from simple thin rectangular plates or single passage stone, this would require comparatively high wages for erection and the rigidity of the entire checker work would be 30 come entirely insufficient as the plates or stones would have to be made of very small size and would thus also have a very low resistance moment.

35 Stones having a number of passages are in use for heat accumulators. These stones, however, have the disadvantage that on the further reduction of the cross section of the passages the stones become too small and lead to difficulties in construction. If, however, a large number of 40 small passages are assembled in large stones then both at the edge of the stone and also when assembling a number of similar stones unequal wall thicknesses are obtained. Such stones when erected vertically with stones having the same 45 surface area, but which have smaller or larger passages, have the disadvantage that these passages are wholly or partly covered.

The object of the present invention is to obtain a high technical effect by the provision of 50 larger vertical heating surfaces with a favourable ratio of the free passage area and the weight of the stone and, by the use of stones of predetermined shape, to eliminate retarding resistances to flow and to obtain absolutely uniform passages 55 throughout the separate layers, substantially the same total cross section of the passages through the entire checker work, and at the same time

the highest possible rigidity of the checker work.

The invention will now be described with reference to the accompanying drawings, wherein:

60 Figure 1 is a vertical section of a heat accumulator constructed in accordance with the invention. In this figure the various zones of the checker work are indicated diagrammatically by rectangles.

65 Figure 2 is a vertical section of the checker work to a larger scale.

70 Figures 3 to 9 show plans of the various types of stones which are used in the superposed zones in order to enable the result of the invention to be obtained.

75 Figures 10 to 13 show the ratio of the internal widths of the passages in the various zones.

A is the complete heat accumulator, B the combustion shaft for the rising gases, C the 80 cupola and D the checker work in which the gases pass downwardly. The uppermost zone I of the checker work consists of stones e with

85 passages in the form of Laval nozzles as shown in plan in Figure 3. The term "Laval nozzle" as used in this specification and claims means an orifice or inlet of a passage formed in such a manner that in the direction of flow of the fluid to be transported the cross-section of the passage is first contracted or narrowed by rounding off the 85

edge of the surrounding wall, and then again enlarged, (see the three passages of the uppermost layer in Figure 2). A characteristic feature of 90

a "Laval nozzle" is that the transformation of the energy of a flowing liquid is effected therein without a loss of energy. There then follow layers f (Figure 4) of a checker work formed by the 95 assemblage of rectangular rounded plates of the same thickness of wall with square passages. There then follows a layer g (Figure 5) of stones with passages therein for converting the increased pressure into velocity and then a further checker work f as above described formed of rectangular rounded plates.

100 For the purpose of conducting the gases to the succeeding checker work having smaller passages there are provided stones h having passages in the form of Laval nozzles (Figure 6) which are enlarged downwardly. These stones h are adapted to fulfil various purposes. In the first case they serve 105 to convert the velocity of the combustion gases in the last layers of the larger checker work zone into pressure energy by reason of the enlargement of the nozzle shaped passages, secondly to connect a single passage with four smaller 110 passages located directly underneath it and having the same total area, and finally this stone renders it possible to so connect together the various zones of the checker work that the flow

of gases therethrough is effected substantially without loss.

There now follows a Zone II formed of stones indicated at i, f, g, f, h , which in the same area have four times as many passages as the stones in Zone I. The last layer of stones h in the Zone I is mounted on a layer of stones i (Figure 7) having passages in the form of Laval nozzles which very effectively lock the transitory stones h by the raised crosses in the form of Laval nozzles provided thereon.

There now follows a Zone III formed of stones i, i' and finally transitory stones h which in the same area have sixteen times as many passages as the corresponding stones of Zone I. The stones i are similar to the stones i in Zone II, whilst the stones i' have smooth passages. At about the middle the Zone III has stones with passages in the form of Laval nozzles, these passages each extending over four passages in the adjacent stones, whereby in the case of clogging up of the separate passages by ashes or the closing of the separate passages by an incorrect positioning of the adjacent stone, the continuation of the closed passage is not placed out of operation.

From the Zone III there extends a Zone IV of which the construction is similar to the Zone III, but of which stones the same area contains sixty-four times as many passages as the stones in Zone 1.

As a closure and for supporting the entire checker work there is provided a cast iron grate l having passages in the form of Laval nozzles.

The fundamental idea of the invention resides therein that the checker work and the division thereof into separate zones is constructed according to a mathematically accurate centre line area system arrangement. In the first zone a indicates the distance between the centres of two oppositely disposed walls of a stone, b the internal width of the passages, and c the thickness of the walls whilst the mathematical relations in the separate zones are according to the following equations:

$$\text{Zone I. } a \cdot a = a^2 \text{ (Figure 10).}$$

$$\text{Zone II. } 4 \cdot \frac{a^2}{4} = a^2 \text{ (Figure 11).}$$

$$\text{Zone III. } 16 \cdot \frac{a^2}{16} = a^2 \text{ (Figure 12).}$$

$$\text{Zone IV. } 64 \cdot \frac{a^2}{64} = a^2 \text{ (Figure 13) and so on.}$$

This shows that the upper Zone I having an area a^2 (Figure 10) is divided into four squares each having an area of

$$\frac{a^2}{4}$$

in Zone II. Zone III is obtained by dividing Zone I into sixteen equal squares each of an area

$$\frac{a^2}{16}$$

or by dividing the separate squares of Zone II each having an area of

$$\frac{a^2}{4}$$

into four further squares each having an area of

$$\frac{a^2}{16}$$

Finally there comes Zone IV, wherein each passage in Zone I is divided into sixty-four equal squares each having an area of

$$\frac{a^2}{64}$$

80

or each of the sixteen squares of Zone III having an area of

$$\frac{a^2}{16}$$

85

is divided into four equal squares each having an area of

$$\frac{a^2}{64}$$

90

The determination of the internal width of the square passage in the separate zones is determined according to the following equations:

$$\text{Zone I. } b = a - c.$$

$$\text{Zone II. } \frac{b}{2} = \frac{a}{2} - \frac{c}{2}$$

$$\text{Zone III. } \frac{b}{4} = \frac{a}{4} - \frac{c}{4}$$

100

$$\text{Zone IV. } \frac{b}{8} = \frac{a}{8} - \frac{c}{8}$$

in which the value of c (thickness of the wall) may vary. Finally it is also necessary to consider the thickness of the walls and in this connection the following is generally usual.

$$\text{Zone I. } c = a - b.$$

$$\text{Zone II. } \frac{c}{2} = \frac{a}{2} - \frac{b}{2}$$

110

$$\text{Zone III. } \frac{c}{4} = \frac{a}{4} - \frac{b}{4}$$

$$\text{Zone IV. } \frac{c}{8} = \frac{a}{8} - \frac{b}{8}$$

115

The quadratic centre arrangement resulting therefrom for the passage chain is the essential feature of the new arrangement. In this centre arrangement there may also be included besides square passages, round, polygonal or other passages.

By the mathematically accurate quadratic division and subdivision of the structure there are obtained as a result of this basis of construction 125 the following:

1. In each zone there is throughout exactly the same total passage area.

2. In each zone there is throughout exactly the same total thickness of stone.

3. In all the zones there is the same weight per cubic meter of constructional area.

4. In all the zones there is the same free passage area per square meter of constructional area.

5. There is no overlapping as the passage of the first zone is divided into four square passages in the second zone, into sixteen square passages in the third zone and finally into sixty-four square passages in the fourth zone (Figures 10 to 13).

For obtaining the advantages set out above the heat accumulator is provided with the following improvements:

1. The upper layer of stones e of the checker work is provided with passages in the form of Laval nozzles for the purpose of converting the pressure energy existing in the upper passages into velocity energy.

2. For eliminating deviations which unavoid-

145

150

ably occur when erecting an ordinary checker work by reason of non-uniform rectangular stones, the stones for the checker work are rounded off or inclined at the edges, so as to form 5 passages which are enlarged in the manner of nozzles.

3. The succeeding layer of stones *g* having 10 passages in the form of nozzles (Figure 5) must fulfil the following condition: After the pressure energy of the gases of combustion in the upper stones having passages in the form of Laval nozzles has been converted into energy of flow the 15 velocity at which the gases must flow through will decrease very rapidly by reason of the long path. If stones having passages in the form of nozzles as shown in Figure 5 are inserted at suitable intervals and provision is made for the reduction in volume of the heating gases by dimensioning the cross sectional area of the 20 passages for the purpose in view, then it is possible in accordance with the invention to again increase the velocity of the heating gases which has become insufficient in the passages and substantially improve the heat accumulation.

25 4. For obtaining a passage of gas from one zone of the checker work to the next, which is as free as possible from disturbance, stones *h* having passages in the form of Laval nozzles are provided, which connect a single passage located above them with four separate smaller 30 passages located underneath them, and having the same total area whilst further passage stones *g* connect together in the lower zones any suitable number of passages in such a manner that 35 in the case of clogging up of the separate passages by means of ashes, incorrect positioning or collapsing, the passages in question are not rendered inoperative along their whole length. In this case the bridged passages of all the lower 40 stones of the checker work are in the form of Laval nozzles *i* so as to avoid any resistance to flow.

5. The lowest zones of the heat accumulator are constructed from separate novel stones *i* for 45 forming checker work which whilst having the same thickness of wall possess a maximum heating surface and weight of stone with the highest rigidity. These stones are of such a shape as though square pipes had been formed integral 50 at their side surfaces and then divided into suitable sections by diagonal cuts, or by cuts through passages at distances which are a multiple of the width of the passage and the thickness of the wall.

55 Briefly stated the following improvements and advantages are obtained from the invention.

(a) Conversion of the pressure energy existing above the uppermost passage zone into energy of flow.

60 (b) The inaccuracies in the assemblage of an ordinary checker work are eliminated by rounding off or inclining the edges of the stones thus also obviating contractions and accumulations.

(c) The stone *g* with the passages in the form 65 of nozzles increases the velocity of the gases which has become insufficient and may bridge over a number of passages in the lower zones.

(d) In passing subsequently to the subdivided zones of the checker work the existing velocity is converted in the enlarged passages in the stones into pressure and when entering the smaller passages is again converted into velocity 80 by nozzles.

(e) The new stone *i* is provided in cross section with a suitable number of equally large passages having all the same thickness of wall between the heating surfaces and may be made 85 in the form of a suitably large block even when provided with the smallest passages.

(f) The square shape and the square centre arrangement of the passages when erecting multi-apertured stones in a checker work formed of a number of stones enables inexpensive checker plates of known construction to be used in the upper zones and thus reduces the cost of the 90 complete checker work.

(g) The provision of the cast iron supporting 95 grate with passages in the form of Laval nozzles.

The cleaning of a heat accumulator constructed by means of stones for the checker work in accordance with the present invention can be 100 effected easily in the known manner, the checker work is extremely certain in operation and affords the maximum thermal efficiency.

We claim:—

1. In a heat accumulator of which the checker work is divided into various superposed zones, a 105 layer formed of stones with apertures the cross section of which substantially follows the converging sides of an isosceles trapezoid continued adjacent the shorter one of the parallel sides of 110 the said trapezoid by two divergent quarters of a circle.

2. In a heat accumulator of which the checker work is divided into various superposed zones, a 115 layer formed of stones having inlet and outlet openings the cross section of which substantially follows the converging sides of an isosceles trapezoid continued adjacent the shorter one of the parallel sides of the said trapezoid by two divergent quarters of a circle.

3. In a heat accumulator of which the checker work is divided into various superposed zones, a 120 layer adjacent to the cupola formed of stones with apertures the cross section of which substantially follows the converging sides of an isosceles trapezoid continued adjacent the shorter one of the parallel sides of the said trapezoid by two divergent quarters of a circle.

4. In a heat accumulator of which the checker work is divided into various superposed zones, 125 passages extending through the said checker work and decreasing in diameter from one zone to the next lower one in the ratio of 2:1, the stones of each layer being arranged in such a manner that the centers of the passages coincide with the intersections of equidistant lines crossing at right angle, and the layers being superposed in such a manner that each passage of one layer is continued by four passages of the subsequent 135 layer.
